MARKER FOR HIGHWAY POLES

Filed Nov. 4, 1931

INVENTOR
By Merritt M. Brown
W. H. Williamson, Atty.

UNITED STATES PATENT OFFICE

MERRITT M. BROWN, OF PHILADELPHIA, PENNSYLVANIA

MARKER FOR HIGHWAY POLES

Application filed November 4, 1931. Serial No. 572,929.

My invention relates to new and useful improvements in a marker for highway poles, and has for one of its objects to provide a simple and effective device of this character which may be easily and quickly attached to poles, trees, or other similar supports along the highways for the purpose of identifying or showing the exact location of said poles, trees, or other similar supports to drivers of vehicles, whereby the sides of the road are readily discernible and whereby such road side obstructions are plainly visible at night when rays of light shine upon the same.

Another and very essential object of the invention is to provide a marker for electric wire supporting poles especially, which embody "safety first" principles by eliminating all upwardly projecting sharp edges to prevent injury to a lineman who may either purposely or accidentally slide down the pole.

Another object of the invention is to provide a pole marker of unique shape which is adapted snugly or tightly fit on all types of poles, either plain, painted or creosoted wooden poles, whether straight, crooked or raked.

Another object of the invention is to provide a marker of the class described which will provide ample climbing space for linemen, although occupying a considerable vertical space on the pole and thereby preventing mutilation of the marker by a lineman's climbing spurs.

Another object of the invention is to produce a marker for highway poles embodying a number of independent units which are mounted upon a support in vertical spaced relation permitting the use of any number of units necessary to make them visible at a sufficient distance to guide the driver of a vehicle along the highway, it being necessary to use a greater number of the units where higher elevations are encountered and a less number on poles situated at lower elevations.

A further object of the invention is to provide a marker which while being disposed over a rather large area of the sup-

port, requires less material than would be necessary to completely cover the same area of the support, thereby accomplishing a saving in material so that the use of such a marker is really economical and the cost of installation is very low.

A still further object of the invention is to provide a marker for highway poles, each unit of which is crescent shaped so that when two or more of said units are used to produce a marker, the upper edge of the center of a lower marker unit will be substantially in the same horizontal line as the ends of the adjacent higher marker unit, so that some portion of one or more of the units will be visible at all points from the ground line of the pole to the upper marker unit when a narrow horizontal light beam from an automobile head light shines upon the pole.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is a face view of one of the marker units constructed in accordance with the present invention when laid out flat.

Fig. 2 is an edge view thereof after being given a general curved shape prior to mounting the same upon a pole or other similar support.

Fig. 3 is a side elevation of the lower part of a pole showing the marker produced from three units mounted upon the pole and illustrating how the marker will appear to the operator of a vehicle approaching the pole.

Fig. 4 is a view at right angles to Fig. 3, when facing and looking at the left hand side of said Fig. 3.

Fig. 5 is an enlarged vertical sectional view of one of the units at about the center thereof.

Fig. 6 is a side elevation of a serrated spike

constituting one type of fastening device for the marker units.

Fig. 7 is an end view thereof.

Fig. 8 is a view of an entire wire supporting pole on a reduced scale illustrating the invention in a manner similar to that shown in Fig. 3.

In carrying out my invention as herein embodied, 10 represents a crescent shaped marker unit produced from metal or other suitable material having weather and certain chemical resisting characteristics. The unit is preferably produced by stamping the same from sheet metal in a crescent shape as shown 15 in Fig. 1 and then curving the same lengthwise as shown in Fig. 2, and such curve has a radius less than the radius of the smallest pole on which the marker is to be used, so that the ends must be sprung apart farther 20 than they are normally spaced to permit the unit to be passed about the support and when the ends are released will spring into place, causing the unit to snugly fit its support where it may be secured by any suitable fastening devices, such as serrated spikes 11 having 25 large rounded heads 12.

Two holes 13 in vertically spaced relation are provided at the center of the unit for the reception of the fastening devices and another hole 14 is provided at each end, also for the reception of fastening devices.

Each unit is also preferably curved outwardly from edge to edge as shown in Fig. 5, which permits the unit to more closely or 35 more perfectly fit its support because from a practical working standpoint only an edge contact is made and such edge can be made to more readily fit any deformations than if an attempt is made to cause the entire surface of the unit to fit the irregularities of a 40 pole or other similar support.

A narrow groove 15 may be fashioned in the inner surface of the unit in proximity to its upper edge and parallel with the entire 45 length of said upper edge, thus producing a bead 16 on the exterior surface and a small rearwardly projecting lip 17 along the upper edge. This arrangement will insure an absolute close fit of the upper edge of the 50 unit against its support so that a person's body, wearing apparel or supporting strap and spurs will readily slide thereover, and to further insure against any protruding sharp edge, the lip 17 may be faced or embedded 55 into its support so that a portion of the outer face of the marker unit will practically merge with the outer surface of its support and anything sliding along the pole will pass on to the unit without hindrance.

60 Any number of units are used in vertical spaced relation to produce a marker such as illustrated in Figs. 3, 4 and 8, wherein a very large area of that part of the pole which is visible to drivers of vehicles along 65 the highway is occupied by the marker, yet

the amount of material required is relatively small so that such a marker is very cheap to produce. The spacing of the units of the marker leaves a sufficient amount of the pole exposed for the use of linemen's spurs thereon making it unnecessary for the linemen to penetrate and thereby mutilate the marker.

70 Another advantage of a marker of this kind is the ornamental effect that it produces outside of its utility and as will be obvious, each unit may carry any suitable ornamentation, designation devices or coloring and they can be arranged so as to have a definite contrast relative to the support in order to make them plainly visible at close distances while 75 blending into surrounding landscape, whereby they will be practically invisible at greater distances.

80 Another advantage of the unique shape of the units is that they do not have to be mounted absolutely concentric to each other nor do the ends have to be in the same horizontal line to make them visible for the results desired and still they will not be unsightly.

85 It is a well known fact that public service companies employing poles for supporting their power lines generally prohibit the use of signs or markers of any kind upon the poles, because they produce grave hazards for the lineman who must climb such poles, because of protruding nail or tack heads, and sharp edges or corners of signs which cannot be made to snugly fit all shapes of poles. Should a person climbing a pole miss his 90 footing and slide down the pole, he is likely to be injured by protruding tacks or nails or sharp edges or corners of signs, and the injury may result in permanent disability or even death, which would subject the company to large 95 damage suits. These disadvantages are entirely overcome by my invention, since the shape of the marker units causes at least the upper edges to closely and snugly fit the poles, and the heads of the fastening devices being 100 round, it is practically impossible for a person to be injured or his clothing damaged.

105 In actual practice, each unit is first fastened at its center by two fastening devices and each end of the unit then separately drawn into place regardless of the position it assumes, so long as the upper edge is snug against the pole and then each end finally secured in place by a single fastening device.

110 Of course it is to be understood that my invention is not to be limited to the exact details of construction herein shown as these may be varied within the limits of the appended claims without departing from the spirit of my invention.

115 Having thus fully described my invention, what I claim as new and useful is:—

120 1. In a marker for highway poles, a crescent shaped unit curved outwardly perpendicularly to its length.

125 2. In a marker of the kind described, a

crescent shaped unit curved longitudinally and also outwardly perpendicularly to its length.

3. In a marker of the kind described, a 5 crescent shaped unit, an outwardly projecting concavo-convex rib formed parallel with and adjacent to its upper edge, and a lip produced between said rib and the upper edge of the unit.

10 4. In a marker of the kind described, a crescent shaped unit, an outwardly projecting concavo-convex rib formed parallel with and adjacent to its upper edge, and a rear- 15 wardly projecting lip produced between the said rib and the upper edge of the unit.

5. In a marker for highway poles and the like, a unit having the general outline of a crescent curved longitudinally to fit a support which is substantially round in cross

20 section and curved vertically whereby the edges of the unit will first contact the support on which it is placed, said unit having a pair of vertically spaced holes at the center and one hole at each end, a rib projecting

25 from the outer face of said unit and produced by the formation of a groove in the inner face thereof adjacent to and parallel with the upper edge of the unit, and a rear- 30 wardly projecting lip formed from the unit material between the rib and said upper edge and adapted to be embedded in the support.

6. A marker for highway poles consisting of a plurality of crescent shaped units secured to a support in vertically spaced relation.

35 7. A marker of the kind described, consisting of a plurality of crescent shaped units for attachment in vertically spaced relation to a support which is substantially circular 40 in cross section, each of said units being curved longitudinally to primarily practically fit about the support and having two holes in vertically spaced relation at the center and one hole at each end for the reception of fastening devices to secure the units of the marker in place.

45 8. A marker of the kind described, consisting of a plurality of crescent shaped units for attachment in vertically spaced relation 50 to a support which is substantially circular in cross section, each of said units being curved longitudinally to primarily practically fit about the support and having two holes in vertically spaced relation at the center and 55 one hole at each end for the reception of fastening devices to secure the units of the marker in place, and each unit also being vertically curved outward to provide a limited contact surface along the edges for engagement 60 with the support.

9. The structure set forth in claim 8, in combination with an outwardly projecting rib formed by the production of a groove in the inner face of each unit adjacent to and 65 parallel with the upper edge of each unit,

and a lip between said rib and upper edge of each unit to be faced into the support.

10. In combination with a pole, a marker 70 consisting of a plurality of crescent shaped units curved longitudinally to fit and mounted in vertically spaced relation upon said pole so that the top of the center of each lower unit is substantially in line with the lower edges of the ends of the adjacent upper unit, 75 said units being vertically curved outward, outwardly projecting concavo-convex ribs formed from the units adjacent to and parallel with the upper edges thereof, lips produced from the units between said ribs and upper edges, which lips may be hammered 80 into the support, each of said units have two vertically spaced holes at the center and one hole at each end, and fastening devices having large round heads inserted through the holes into the pole.

85 In testimony whereof, I have hereunto affixed my signature.
